UNITED STATES PATENT OFFICE.

CHRISTIAN AALBORG, OF PITTSBURGH, PENNSYLVANIA.

ATTACHMENT FOR VACUUM CLEANERS.

Application filed June 18, 1924. Serial No. 719,703.

My invention relates to attachments for vacuum cleaners and particularly to tool attachments for vacuum cleaners of the type illustrated and described in my copending 5 application, Serial No. 652,684, filed July 20, 1923, for vacuum sweepers.

The primary object of my invention is the provision of a vacuum cleaner with an auxiliary cleaner having a suction opening and 10 a discharge opening therein.

Another object of my invention is to provide an attachment for the casing of a vacuum cleaner for communicating the sucking and blowing action in the cleaner to a tool 15 in order that a blowing and a vacuum effect may be exercised at a distance from the casing.

A further object of my invention is to 20 provide an attachment which may be inserted into the path of travel of air in a vacuum-cleaner casing to interfere with the circulation of air in a closed path in the casing, to lead the air away from the casing to a tool and to conduct air from the tool 25 to the casing.

A still further object of my invention is to provide connections between a vacuum-cleaner casing and a tool, for drawing air 30 through the suction nozzle on the tool and conducting it to the casing and for leading air from the casing to the tool and forcing it through a discharge nozzle on the tool.

In the drawings, Figure 1 is a side elevational view of my attachment applied to a 35 casing, parts of the casing and parts of the tool being shown in section.

Fig. 2 is a detail top plan view showing the closure disc and the parts of the casing to which it is immediately applied.

40 Fig. 3 is a detail plan view of the tool, and

Fig. 4 is a vertical sectional view on the line IV—IV of Fig. 2.

The vacuum-cleaner casing comprises a 45 hood 10 and a dome 11 secured thereto which may be constructed as illustrated and described in my above-mentioned copending application. The hood 10 has a longitudinal air channel 12 therein extending along its upper wall. Air is drawn from a suction 50 nozzle 13 through the channel 12 by a fan 14 and forced by the fan into a dust chamber 15. The hood 10 is provided with a flange 16 within which a pan 17 is fitted and 55 detachably secured in position by clips 18, as described in my copending application.

The pan 17 is formed in all respects similar to the pan in said application, except that it has an extension 20 formed on its front end.

The extension 20 is substantially flat and 60 is provided with a downward deformation 21 which provides clearance for a brush 22. The extreme front edge of the extension 20 is formed into a flange 23 fitted upwardly about the nozzle 13.

The pan 17 carries a filter 24, as described in my above mentioned application, and a passage 25 is provided longitudinally of the pan 17 for air forced through the dust chamber 15. The passage 25 communicates 70 with the nozzle 13 and the channel 12 so that there is a substantially closed path of travel for the air.

The hood 10 has a circular opening 26 in its upper wall and is provided with a shoulder 27 bordering the opening. A closure disc 28, constituting a part of the attachment, is provided with a peripherical flange 30 to engage the shoulder 27 and may be held in position by means of thumb screws 80 28a or other clamping devices. The closure disc has an outlet orifice 31 therein about which a nipple 32 is formed and an inlet orifice 33 about which a nipple 34 is formed.

A hose 35 is secured to the nipple 32 by 85 means of a connection 36 which is slipped over the nipple and maintained in position by a bayonet joint 37. A hose 38 is secured to the nipple 34 by a connection 40 and a bayonet 41. The hose 35 is secured to a tool 90 42 by a connection 43, and the hose 38 is secured to the tool 42 by a connection 44. The tool 42 is provided with a suction nozzle 45 extending its entire width and with a discharge nozzle 46 extending alongside the 95 suction nozzle and immediately adjacent thereto.

An air passageway 47 is provided in the tool to communicate with the hose 38 and the suction nozzle 45. A similar air passageway 48 is provided to communicate with the hose 35 and the nozzle 46. The passageways are separated by a partition 49 the edge of which, extending between nozzles 45 and 46, is substantially horizontal. The 105 partition is twisted in shape and, at its other end, is substantially vertical.

A partition 50 is formed on the closure disc 28 and extends transversely from wall 51 to wall 52 of the air channel 12. The 110 partition, at its bottom edge, engages bottom wall 53 of the channel 12 and is pro-

vided with a slot to receive a tubular housing 54 which, as described in my copending application, surrounds a shaft 55. The bottom wall 53 has an opening which is covered by a plate 56. A lug 57 is formed on the plate 56 and projects upwardly to engage the surface of the housing 54.

The slot in the partition 50 is of such form and dimensions as to ensure a close fit 10 against the housing 54 and the edges of the lug to completely close the air channel 12.

In the operation of the device, the fan 14 exerts a suction action in the air channel 12 which is communicated to the hose 38 15 and thence to the air passageway 47 and the suction nozzle 45. The fan also drives air downwardly through the dust chamber 15 over the pan 17 past the brush 22 and into the suction nozzle 13 on the hood whence it 20 is forced upwardly and through the outlet orifice 31.

Since the partition 50 prevents the passage of air rearwardly thereof, it is forced into the tube 35 and thence into the tool 42 25 through the passageway 48 and the discharge nozzle 46. The tool 42 is manipulated by hand after the common fashion of manipulating cleaner tools, and the suction and discharge nozzles are brought into contact with the surfaces of objects to be 30 cleaned. As the discharge nozzle is immediately adjacent to the suction nozzle, the dirt freed by action of the air is sucked in so that the operation of the tool results in 35 no inconvenience to the user, and efficient action results from the simultaneous blowing and sucking. The air is drawn through the suction nozzle and forced by the fan 14 through the filter 24 so that it is cleaned and 40 its path of travel through the tool 42, the hose 35 and 38 and the casing is substantially closed.

The filter may be cleaned by removing the pan 17 on the release of clips 18. The attachment may be removed by withdrawing the thumb screws 28a and pan 17 may be removed, and the vacuum cleaner may be used as described in my above-mentioned application.

The invention is not limited to the precise 50 embodiment disclosed as it is capable of being changed and modified extensively, and a substantial range of equivalents within the scope of the appended claims is contemplated.

I claim as my invention:

1. A vacuum cleaner comprising a hollow casing provided with a horizontal partition separating the space therein into lower and upper communicating passages, a motor supported at the rear of the casing with its shaft extending into the casing, an impeller on the motor shaft and having an inlet from the upper passage and an outlet into the lower passage, means insertible from the top 60 of the casing through an opening therein to serve as a barrier and deflector to permit the current of air drawn by the impeller to enter the upper passage through the opening in the casing on one side of the barrier, and to permit the air forced through the lower 65 passage to pass through the opening in the casing on the other side of the barrier, and means whereby the air currents may be utilized externally of the casing as a cleaning 70 medium.

2. A vacuum cleaner comprising a hollow casing provided with a horizontal partition separating the space in the casing into an upper and a lower passage, a motor-driven 80 impeller for drawing a current of air from one passage and forcing it into the other passage, at one end of the passages, means insertible through an opening in the casing near the other end of the passages for separating the passages and serving as a barrier therebetween to permit the current of air to be drawn in through the one passage through said opening on one side of the barrier and forced through the other passage and out 85 through said opening on the other side of the barrier, and means whereby the currents of air so established may be utilized beyond the cleaner casing.

In testimony whereof, I have hereunto 90 subscribed my name this 6th day of June, 1924.

CHRISTIAN AALBORG.
